Engelmann

UNITED STATES PATENT OFFICE.

THURE DAHL, OF NEW YORK, N. Y., ASSIGNOR TO LIGHTOLIER COMPANY, A CORPORATION OF NEW YORK.

LIGHTING FIXTURE.

1,417,145.

Specification of Letters Patent. Patented May 23, 1922.

Application filed February 15, 1921. Serial No. 445,081.

To all whom it may concern:

Be it known that I, THURE DAHL, a subject of the King of Sweden, and resident of New York city, in the county of New York and State of New York, have invented certain new and useful Improvements in Lighting Fixtures, of which the following is a specification.

My present invention relates to lighting fixtures, more particularly to that type of pendent fixture which includes a shade of diameter substantially larger than that of the lamp or lamps.

In pendent lighting fixtures, more particularly where chains are connected to the rim of an open-top shade for suspending the same, such chains usually appear to the eye as essentially structural elements which detract from the beauty of the fixture, and while holding the shade from dropping do not prevent it from swaying excessively with respect to the suspension member. On the other hand, where the shade is in the form of a dome, substantially closed at the top and depends directly from a suspension member, the construction is relatively heavy and expensive.

It is an object of the present invention to provide a lighting fixture embodying an open-top shade, the structural elements of which fixture shall contribute to an elegant and distinctive appearance.

According to a feature of the invention, the fixture is provided with an outwardly projecting rigid structure by which the open-top frame is supported. In the preferred application to pendent lamps the lower end of the suspension member is in the form of a hub from which radiate a plurality of equidistant rigid bracket arms, the shade being carried at substantially the outer ends of said arms. Preferably the arms have an ornamental ogee shape and extend generally outwardly and downwardly from the hub to the upper part of the shade rim, thereby affording appropriate stiffness for carrying the shade although a slender arm construction is employed, and providing a distinctive and elegant appearance.

In the specific and preferred embodiment disclosed, the bracket arms are secured to the hub by means of screws extending through tongues or projections formed integrally with the inner ends of the arms, so that the weight of the shade applied near the

outer ends of the arms will cause the tongue to more tightly engage the hub.

Other objects and features will be in part obvious and in part pointed out hereinafter.

In the accompanying drawings in which is shown one of the various possible embodiments of this invention,

Fig. 1 is a fragmentary side view of the fixture, the hub and shade being shown in section, the latter in dotted lines, and;

Fig. 2 is a fragmentary bottom plan view.

Referring to the drawings, I have shown a portion of a pendent lighting fixture, the suspension member (not shown) hanging from the ceiling and having at its lower end an ornamental body member, the lower portion of which is shown at 2 and is preferably a cup-shaped hub with its rim 3 facing downwardly. Extending into said cup-shaped member with little clearance is an electric lamp socket 5 coaxial with the body member, and secured thereto in the usual manner by means of the headed screw 6.

The shade is indicated in dotted lines and in the preferred form is of the known open-top type comprising an inner wire structure 7 upon which is secured the silk or other fabric of the shade, and an outer frame portion 8 of metal or equivalent material having an inner loop 9 resting upon the upper end of the structure 7. Wire loops 10 for supporting the shade extend inwardly from the wire structure 7 and serve for attaching the shade to the fixture.

For supporting the shade I provide means formed rigid with the hub and extending outwardly therefrom and preferably providing legs 11 with outstanding feet 12 extending within the shade, on each of which feet is an integral upstanding pin 13 over which the loops 10 on the shade are passed, thereby supporting the shade in place against shifting about its axis, and without the use of special clamping or other separate, positive or adjustable securing means.

In the preferred embodiment I employ a plurality of radially extending arms 14 at equal angular intervals, such arms extending outwardly from the hub and having the shade supporting portions above described formed integrally at the outer ends thereof. The inner ends of the arms are provided with integral flat tongues 15 contacting the rim 3 of the hub member, each tongue being secured to the hub by means of a pair of

screws 16 extending therethrough and into the hub. The tongues preferably extend somewhat beyond the inner periphery of the rim as at 17 and below a usual form of flange 5 18 on the lamp socket, so that the latter will be prevented from dropping should it be disconnected.

The arms may have any appropriate form or design preferably ornamental. In the 10 preferred embodiment bracket arms of ogee or S-shape are employed as shown. Structurally this provides a rigid support for the shade although the arms are slender, for, the greatest thickness and, therefore, the 15 greatest stiffness is in a vertical line, that is, in the direction in which the strain is applied. The arrangement shown provides a truss-like support in that any tendency for the weight of the shade to draw the outer 20 ends of the arms downwardly would result in the tongues 15 being drawn slightly upwardly about the screws 16 and firmly against the rim 3 of the hub, thus assuring the desired rigidity of the assembly. The 25 symmetrical arrangement of the arms and the axial arrangement of the hub and shade result in the strains being evenly balanced and the weight evenly distributed, and the shade being accurately and firmly supported 30 in a horizontal plane. The slender supporting bracket arms 14 as shown in the drawings are in visible position above the shade and afford to the entire fixture an elegant, artistic and distinctive appearance.

35 It will be seen that no securing or connecting parts intervene between the hub and the lamp socket so that the hub need be made only slightly larger in internal diameter than the socket and even though thick-walled and strong, its external diameter will 40 remain small, and will provide the desired ornamental effect in combination with the relatively long radiating arms, while the danger of jamming of any intervening securing member between the hub and socket 45 is entirely eliminated. The radiating arms being secured against the rim at the bottom of the hub by upwardly extending screws or equivalent means, the mechanical connections 50 between the arms and the hub remain invisible when the fixture is viewed in installed position. It will also be seen that since the supporting means for the shade extends entirely within the same from the upper end thereof, it is invisible from the exterior and by the arrangement of parts as 55 shown, the upper periphery of the shade comes substantially in the plane of the outer ends of the arms. Thus the beauty of the 60 fixture is in no way detracted from by any visibility from the exterior when installed, of screw, bolt, rivet heads, or other mechanical fastening means. Since the radiating arms are of rigid construction, the weight 65 of the shade bears directly downwardly

upon the supporting feet at their outer ends, and the weight of the shade will not draw the radiating arms inwardly and exert strain upon the frame of the shade, as might be the case if the radiating arms were flexible 70 rather than rigid.

Since the shade rests upon the arms by gravity and is not clamped in place, its frame is, moreover, free to expand or contract with changes of temperature resulting 75 particularly from putting the light on or off and this without producing any extra strain upon the shade.

The broader features of the invention can be embodied in a construction in which the 80 arms are joined into an integral plate; also in constructions in which the arms are formed integrally with the body or secured thereto by means other than the screws disclosed.

85 One distinctive design of lamp in which the present invention is preferably embodied is shown in my copending design application, Serial No. 434,156, filed Dec. 30, 1920. It will be seen that all chains or other 90 ungainly supporting elements are eliminated as are heavy dome structures, the outwardly extending bracket arms 14 providing a pleasing and ornamental appearance and nevertheless affording the mechanical strength 95 requisite for firmly supporting the shade.

It will be understood that though the invention is preferably applied to pendent lighting fixtures, some of the features thereof may be applied to floor lamps or other fixtures and that it is not limited in its uses to electric fixtures but may also be employed in gas fixtures.

It will be understood that although the shade supporting parts 11-12 are preferably cast in one piece with the arms 14 as shown, they may be made of separate pieces screwed, soldered or otherwise connected with respect to the arms, the term "integral" employed in certain of the claims to define 110 the relation of the arms to the shade carrying elements being intended to define any relation in which all these combined elements constitute a substantially rigid unit, as distinguished from a construction in 115 which these elements are movable or displaceable with respect to each other in the process of applying or removing the shade.

It will thus be seen that there is herein described a structure in which the several features of this invention are embodied, and which attains the various objects of the invention and is well suited to meet the requirements of practical use.

As many changes could be made in the 120 above construction, and many apparently widely different embodiments of this invention could be made without departing from the scope thereof, it is intended that all matter contained in the above description or 130

shown in the accompanying drawings shall be interpreted as illustrative and not in a limiting sense.

Having thus described my invention what I claim as new and desire to secure by Letters-Patent is:—

1. In a lighting fixture, in combination, a support, an open-top shade having a plurality of inwardly projecting support elements, a substantially rigid symmetrical carrying structure for said shade including arms radiating outwardly from said support for a distance nearly equal to the radius of said shade, one arm corresponding to each supporting element, said arms being constructed and arranged each to provide a rest for the corresponding support element and to obstruct said shade against rotation about its axis, whereby the shade is carried without positive clamping or securing means.
2. In a lighting fixture, in combination, a support, an electric socket mounted thereon, a cup-shaped hub enclosing the upper end of said socket and carried by said support, a plurality of identical rigid arms, each having an integral portion extending under and directly in contact with the bottom of the rim of said hub and each secured thereto, each arm projecting outwardly from the rim for a substantial distance, and means substantially at the outer ends of said arms for supporting a shade in position co-axial of said hub.
3. In a lighting fixture, in combination, a support, a hub or body carried thereby, a plurality of relatively stiff arms arranged at substantially equal angles and projecting outwardly and curved downwardly from said hub, each said arm having an integral tongue at its inner end extending under the lower surface of said hub, screws securing said tongues to said hub, and means at the outer ends of said arms for supporting a lamp shade in position coaxial of said hub.
4. In a pendent lighting fixture, in combination, a suspension member, a cup-shaped hub member extending downwardly from the lower end of said suspension member, a lamp socket extending into said cup-shaped member and carried by said suspension member, said lamp socket having a flange, a plurality of rigid arms radiating outwardly from said hub, each having a portion contacting with the rim of said cup-shaped member and secured thereto and projecting inwardly beyond said rim and under said flange, the outer ends of said arms serving as supporting means for a lamp shade, the innermost ends of said arms serving to prevent said socket and its lamp from dropping should the same be mechanically detached from the suspension member.
5. In a lighting fixture, in combination, a bracket arm having a tongue at one end extending in the general direction of the length of said arm, an integral leg near the opposite end of said arm extending outwardly at right angles to the general direction of the length of said arm and having a foot parallel to said tongue for supporting an element of a shade.
6. In a lighting fixture, in combination, an open-top shade having inwardly extending supporting loops below the upper ends thereof and a fixture therefor including a plurality of radial arms having integral downwardly extending supporting feet for said loops whereby the upper end of said shade will be substantially in the same plane as the outer ends of said arms, and said loops and feet will be concealed.
7. In a lighting fixture, in combination, an axial support, a hub coaxial therewith constituting a cover for a lamp socket to be carried by said support, said hub having a lower rim, a plurality of identical arms in radial planes extending outwardly from said hub, each said arm having an integral portion extending under and secured against said rim, each said arm having a shade supporting foot near the outer end thereof for extending within a shade to be supported on said feet.

Signed at New York city, in the county of New York and State of New York this 11 day of Feb. A. D. 1921.

THURE DAHL.
